WINDOW FRAME

William Howarth, Milford, Conn.

Application May 24, 1944, Serial No. 537,096

7 Claims. (Cl. 20—12)

1

This invention relates to a window frame. It is an object of this invention to produce a new and useful window frame or casing provided with yieldable side elements which are adapted to loosely and frictionally engage the sash edges throughout the full length thereof.

It is also an object of this invention to produce new elemental features that can be removed readily whereby the weights used may become readily accessible.

It is also an object of this invention to produce a new assembly including the yieldable parts in such a manner so that the sashes will closely fit within the window frame.

It is further an object of this invention to produce a window casing from wood or plastic materials that may be worked in the carpenter's trade and wherein all of the parts may be readily assembled and neatly fitted for its operation.

The features of novelty will be precisely and clearly set forth in the attached specification and drawings.

In the drawings:

Figure 1 is a side elevation shown foreshortened longitudinally for purposes of brevity and being partly in section;

Figure 2 is a bottom view of the device or casing including the arrangement of springs whereby the yieldable elements are attached to each other for yielding pressure upon the side edges of the sash;

Figure 3 is a transverse section showing the casing or frame including sashes as indicated on the line 3—3 of Figure 1;

Figure 4 is a fragmentary view in section taken on the line 4—4 of Figure 3, and also showing the parts broken away to disclose various elements of the assembly;

Figure 5 is an element which is adapted to be detachably connected to one of the yieldable elements of which it is a part;

Figure 6 is a perspective view of one of the riser elements forming a part of the combination of parts comprising the frame;

Figure 7 is a vertical section of the major portion of one side of the frame including the upper portion thereof and indicating how the operating parts are supported by the yieldable means which actuate one of the frictionally-engaging members in the frame;

2

Figure 8 is a transverse section taken on the line 8—8 of Figure 1;

Figure 9 is a perspective view of a portion of one of the yieldable elements;

5 Figure 10 is a perspective view of one of the companion yieldable elements;

Figure 11 is a perspective view of a central guiding strip located between the sashes and also between the yieldable elements; and

10 Figure 12 is a perspective view of a portion of an upright filler element and support.

Referring to the drawings, finishing strips 2 and 9 are secured on the outermost sides of the principal supports 3 and 7, by the usual means.

15 The stool board 1 is also secured in position by conventional means. Yieldable strips 4 and 4' are movably and yieldably located so that these strips may move toward or away from the sash at least one-eighth of an inch. To the left in Figure 3, the yieldable strips 4a and 4b are slidably and yieldably supported by vertical side pieces 3', 6', 6b and portions of the standard 7'. Yieldably mounted strips 4a and 4b are frictionally held in position to engage the edges of the sashes sh.

20 In connection with Figure 7, it is noted that these yieldable strips are provided with spring sockets as indicated at the upper portion thereof, and at the central portion which sockets are each

30 adapted to receive one end of a helical spring of the compression type. Spacer strip 8 in Figures 7 and 8 is also a support for helical springs as indicated at 8s, within the sockets formed therein are helical springs 8sp. These helical springs 8sp are engaged in the sockets at the upper end portions of the yieldable elements 4 and 4' as indicated in Figure 8.

35 It is noted from Figure 1, that the intermediate portion of the frame is provided with a cross piece 12 which also forms a support for the end of a helical spring 12', as in Figure 7. The opposite end of the spring 12' is supported in the socket of the yieldable element 4.

40 Attention is called to the socket 5 located in element 4' of Figures 8 and 10. The block 11 is provided with a tapered upper portion containing a slot 11s. Also the block 11 is reduced on two sides to form a shoulder 14s and a depending leg 14 containing a groove 13 adapted to receive 45 a wire loop 13a as shown in Figure 4. The block

11 is secured to the yieldable strip 4 through the medium of a pin 11p which enters the slot 11s. Below the slot the block is secured to the element 4 by a screw 11f as also indicated in Figure 4.

In this connection it is to be observed that block 11 is detachably secured to yieldable strip 4 of which it forms a part.

Turning to the right side of Figure 3, it is noted that the spacer 3 is provided with a groove 3a which receives a tongue 4t located on the yieldable strip 4. The groove 3a is at least one-eighth of an inch wider than the tongue so that the strip 4 may yield a limited amount within the groove 3a. The strip 6 is rabbeted for more than half of its width as clearly indicated in Figure 11. The strip 6 is frictionally and movably retained in place by the sashes and also by the movable elements with which it is frictionally engaged. The rabbeted portion of strip 6 provides a stop to engage the strip 4, to prevent the said strip from extending too far between said yieldable strips 4' and 4.

In connection with Figures 1 and 2, it is noted that the sill 1 is provided with a groove 1a which provides an insect guard and also reduces the tendency of the sill to warp. The forward end of the sill is provided with a raised portion 1r as clearly indicated in Figure 1. In Figure 2 it is noted that the sill 1 is provided with slotted portions 12s at both top portion and bottom portion of the figure. The slotted portions receive the legs 14, 14' and 14a and 14b, which represent the lowermost portions of the yieldable elements 4, 4', 4a and 4b, as clearly indicated in Figure 3. Portions 14, 14' and 14a and 14b are surrounded by a wire loop such as indicated at 13a, 13b of both Figures 1 and 2. Each loop is provided with the shank 15, 15', terminating in a hook 16, 16' which are engaged respectively in rings on the end portions of tensioned helical springs 17 and 17'. It will be noted that the legs 14, 14', 14a and 14b, are yieldably connected together and urged toward each other through the means of the loops and shank hooks and tensioned helical spring 17, 17'.

In this connection it is pointed out that the yieldable element is connected to an opposed yieldable element on the other side of the frame and that there is direct cooperation between the opposed yieldable elements which engage respectively the associated sides of the sashes.

In Figure 1 it is noted that each yieldable element supports a pulley frame 10a and a pulley 10, whereby the conventional cord and weight may be used in coaction with the sashes.

In Figure 9, the upper portion of the yieldable element 4 is disclosed as having a socket 4s to receive one end of a helical compression spring 8sp, as indicated in Figure 8. The tongue 4t in combination with the groove 3a, forms a stop for the yieldable element 4 so that said element can only have limited movement of at least one-eighth of an inch.

In Figure 7 it is noted that the top piece T is provided with a groove 10b which loosely receives the upper ends of the yieldable elements 4 and 4'.

In order to remove the yieldable element 4, it is merely necessary to remove the sashes. This may be done by removing one of the guides 6a or 6b. After the sashes are removed or at least the front sash, guide strips 6 are removed and the back sash also removed. When this has been accomplished, it is now merely necessary to remove the fastening screw 11f indicated in Figure 4, so that the block 11 may be disengaged from

the strip 4. Strip 4 may now be bodily removed from the frame including its pulley casing and pulley and rope as well as the weight. A similar operation will permit the complete removal of the remainder of the yieldable elements.

In order to reassemble the removed parts a mere reversal of the removing and detaching operations is all that is required. Then the block 11 having the slotted part 11s will again appear in the position indicated in Figure 4. The same identical operations will be performed with reference to the yieldable strip 4a and then the guide strips may be inserted in position just after the back sash has been placed. Since the strips 4' and 4 are yieldable, they may be pressed toward each other, but it will be necessary to push them back to some extent while inserting the sash.

Even though the movable elements are inserted for movement, it must be noted that they can be fitted so closely that no weather stripping will be necessary in connection with the window frame of this construction.

Though the materials used as indicated by the drawings are made of wood, it is evident that most of the parts could be made of suitable plastic material, and could be worked in the same manner as wood by the carpenter.

In connection with Figures 1 and 2, it is to be observed that the sill 1 is provided with a pair 30 of supporting filler strips 1b and 2b each being substantially triangular or wedge-shaped in outline. These filler strips define in each instance one right angular portion 1d, and each is provided in its upper inclined portions with notches 35 1e, 2e, 3e and 4e. These filler strips 1b and 2b abut at one end against the upright filler post 7, 7' and support said posts in proper position with reference to the sill. The upper inclined portion of each filler strip abuts against the sill 1 and each of these filler strips are secured to the sill 1 by suitable fastening means such as nails or screws as indicated at 1c of Figure 1.

Variations of structure or structural details may be resorted to which fall within the range of equivalents, which are shown and described, so long as such variations fall within the scope of the subject matter herein claimed.

What I claim is:

1. In a window frame, having the usual front 50 and rear guide strips for window sashes, in combination with yieldable strips located between said guides, said yieldable strips being spring actuated, and the top portions thereof, and also the lower portions thereof being mounted for limited movement to and from the sashes, said strips being arranged in opposed pairs, and springs being located to actuate each strip toward its opposed strip, whereby each side edge portion of the sash is frictionally and slidably engaged by 55 said yieldable strips, further in combination with a centrally located, movably and removably mounted guide strip located between the adjacent yieldable strips, said guide strip having a stop portion, whereby it is adapted to engage against a surface portion of one of the adjacent yieldable strips.

2. In a window frame, the sub-structure comprising a strip adapted to be suitably mounted and spring actuated within a window frame, said strip having a socket in its upper end portion 60 adapted to receive one end of a compression spring and pulley casing and pulley spaced from said socket, and also having intermediate the length of said element another socket adapted to receive a helical spring of the compression type,

the lower end of said strip having a block secured thereto by a detachable fastener, a pin carried by said strip and projecting therefrom spaced from said fastener and engaging the upper portion of said block, said block being provided with a shoulder on two edges thereof, also having a leg portion depending from said block and shoulder, the lower portion of said leg being provided with a groove to receive a looped fastener.

3. In a window frame, the sub-structure comprising an element which is adapted to be spring actuated for limited movement within a window frame, said strip being provided with a socket in its upper portion adapted to receive a helical spring of the compression type, said strip being slotted and receiving a pulley casing and pulley located in spaced relation from and below said socket, the intermediate portion of said strip having an additional socket for a helical spring, in combination with a block element secured to the lower portion of said strip, said block being provided with a slotted bevelled portion at its upper end receiving a pin projecting from said element and engaging said slotted portion, the block being reduced on two sides to form a depending leg, said depending leg having a grooved portion near the lower end thereof, adapted to receive a looped fastener, said strip and block being additionally secured together by a screw-threaded fastener which passes through the strip, and into said block, whereby said block may be firmly secured to and against one side of said strip.

4. A window frame adapted to receive slidable sashes and having guide means at both front and rear of the sashes and intermediate thereof, at least one of said guide means being yieldably mounted between the sashes, in combination with yieldable sash-engaging strips located in slidable contact with the sash edges, a block secured to the lower portion of each strip, said blocks having depending leg portions extending downwardly from said strips, the lower portion of each leg having a groove therein extending peripherally thereof and receiving a looped fastener extending at right angles thereto, said fastener carrying a shank portion terminating in a hook, said hook engaging a ring secured to each end of a pair of tension springs, whereby said blocks and strips may be yieldably mounted for limited movement to frictionally and slidably engage the edge portions of the sashes.

5. In a window frame having sash guides and yieldably mounted sash-engaging elements located between said guides frictionally and slidably the edge faces of the sashes contained in said frame, said frame having a sill portion with slotted ends receiving depending leg portions extending downwardly from the yieldable elements or strips, said legs and strips being located in op-

posed pairs, each leg of the opposed pair being connected by spring means of the tension type whereby each yieldable strip element is suitably drawn toward the other of its pair to yieldably and slidably engage the edge surface portions of the sash which is adapted to be located between them.

5 6. In a window frame of the class described, said frame having upright stationary parts and a plurality of sash guides, a pair of sash engaging strips located between said guides, and all portions of said sash-engaging strips being spring actuated toward the faces of the sashes to yieldably and slidably embrace the same, in combination with a centrally located spring engaging means comprising a strip extending transversely of and across said yieldable strips, and having the ends thereof secured to upright stationary parts of said frame, spring means extending from said strip to and in engagement with said yieldable elements, whereby the intermediate portions of said yieldable strip elements are yieldingly engaged toward said sashes.

10 7. A window frame comprising upright guide portions for sliding sashes, upright strips mounted between the guides, said upright strips being spring actuated to yieldably engage the side edges of the sashes, spring means located at the upper end portions of said strips, at their intermediate portions thereof, and also at the lower portions thereof, said lower portions being provided with depending legs, said frame also having a top portion and a sill portion, said sill portion being slotted at its ends to receive depending legs which extend a suitable distance below the surface portion of the sill, said strips being arranged in pairs in opposed relation to each other, the opposed yieldable pairs being connected by spring means including connecting means extending across the frame beneath the sill, said frame also having filler supporting strips mounted beneath the sill and secured thereto by any suitable means, the supporting filler strips having slots in the upper portions thereof, which receive the connecting means for the lowermost springs.
